UNITED STATES PATENT OFFICE.

JOHN F. COURSON, OF PITCAIRN, PENNSYLVANIA.

FRICITION DRAFT-GEAR.

1,180,979.

Specification of Letters Patent. Patented Apr. 25, 1916.

Application filed February 8, 1909. Serial No. 476,588.

To all whom it may concern:

Be it known that I, JOHN F. COURSON, a citizen of the United States, residing at Pitcairn, in the county of Allegheny and State of Pennsylvania, have invented certain new and useful Improvements in Friction Draft-Gear, of which the following is a specification, reference being had therein to the accompanying drawing.

10 My invention relates to the class of friction draft gearing or rigging for railway cars, etc., and it has for its object to provide a draft gearing of simple construction and high efficiency, and is designed to utilize the 15 wedging and releasing qualities of wedge blocks between the central buffering member and surrounding friction member or members, having faces disposed at varying angles, together with other features of construction, as shall be more fully hereinafter set forth in the specification and as embodied in the claims.

In the accompanying drawings illustrating the invention:—Figure 1 is a central horizontal sectional view of the complete draft rigging assembled, the parts being in their extended position. Fig. 2 is a vertical sectional view at right angles to Fig. 1 the parts being in the same position. Fig. 3 is 20 a view similar to Fig. 2, showing the parts in compressed position. Fig. 4 is a transverse sectional view on the line IV. IV. of Fig. 3. Fig. 5 is a perspective detail view of the inclosing cylindrical shell for the 25 working parts. Fig. 6 is a similar view of the buffering block which normally engages the draw bar of the coupler. Fig. 7 is a similar view of one of the movable friction blocks. Fig. 8 is a similar view of the wedge block 30 which cooperates with the differential angle wedge blocks. Fig. 9 is a similar view of one of the differential angle wedge blocks.

In the drawings, 2 represents the draw bar of the coupler fixedly connected with 45 the yoke 3 by the transverse bolts 4 in the manner customary in this art, said yoke embracing the casing or cylinder 5 at top and bottom as shown, the yoke and casing being located between the center sills 6.

50 7 is a bearing block or piece set within the rear end of cylinder 5 and having a flanged engagement therewith, against the outer end of which block bears the rounded end 8 of strap 3 with an interposed filling block 9, preferably secured to the end of the strap, as shown.

10 are the front stops which sustain the pulling effect of the draft gear and impart it to the center sills 6, to which the said stops, of angle form, are secured by riveting 60 or otherwise.

11 is the buffering block of the construction shown in Fig. 6, bearing by its front end against the stops 10, and also normally against the rear end of draw bar 2, said 65 buffering block having angularly shouldered wedge faces 12, 12, and a central rearwardly extending block terminal 13 which fits into a receiving socket 14 of a co-acting wedge block 15. Said wedge block 15 is provided 70 at its forward end with oppositely inclined wedge faces 16, 16, of a more acute angle than that of the wedge faces 12, adapted to receive the impact of the interposed differential angle wedge blocks 17, 17, (Fig. 9.) 75

Set within the casing 5 above and below the buffering block 11 and bearing against the inner curved faces of the casing by correspondingly curved faces 18, are the friction blocks 19, 19, comprising a separable friction block made in two halves. Said blocks 19 have substantially semi-cylindrical rear flange portions 20 embracing the rear end of wedge block 15, and providing a flat substantial bearing by their outer faces for the buffering springs. Friction blocks 19 are also provided at their inner sides with wedge faces 21, of more acute angle to the longitudinal center than faces 12 of the buffering block, and approximating the same angle as faces 16 of wedge block 15, but in opposing directions thereto.

80 Interposed between the inner faces of filling block 7 and the outer faces of flanges 20 of friction block 19, are the buffering springs 22, 23 and 24, nested completely together and adapted to interpose increasing resistance either to the impact of buffering in the operation of coupling or in the initial operation of starting the car.

85 The object in the present construction is, as is generally the case in all similar apparatus, to interpose a high degree of frictional resistance between the moving parts and the relatively stationary parts of the apparatus, *i. e.*, between cylinder 5 and the outer faces 18 of friction blocks 19. A further object is to prevent jamming and provide for immediate and easy separation of these parts upon expansion of the springs, 90 and to accomplish these objects I have employed the differentially angled wedge blocks 105 110

17 adapted to be incorporated and to co-act with the buffing block 11, friction blocks 19, and wedge block 15. For such purpose the wedge blocks 17 are provided at their inner front portions with wedge faces 25 corresponding in angle to wedge faces 12 of buffing block 11; on their upper rear portions with wedge faces 26 corresponding in angle to the wedge faces 21 of friction blocks 19; and at their rear inner portions with wedge faces 27 corresponding in angle to wedge faces 16 of wedge block 15.

As observed, faces 26 and 27 are more acute to the longitudinal center than faces 15 25 so that their separating or wedging action to press the friction blocks 19 outwardly by insertion between said blocks and faces 16 is greater than the separating effect of wedge faces 12 of the buffing block 11 when 20 acting on wedge face 25. The object of such construction and the result desired is that the initial effect of either the back movement of the buffing block in buffing or of the forward movement of the friction blocks 19 25 in drawing is to cause an initial movement of the differential angled wedge blocks between the faces of wedge block 15 and faces of friction block 19, and slippage thereon, under pressure, rather than movement of 30 the relatively less acute faces 12 and 25. These angles, however, co-act with the operation of said faces 12 and 25, as indicated in Fig. 3, showing the parts in compressed position and friction blocks 19 bearing by 35 their faces 18 outwardly in tight frictional engagement with the inner faces of casing 5.

A particular advantage of the construction, in addition to the above, is that upon release of pressure the relation of the angles is such that the more obtuse angles 12, 25, facilitate separation and a resulting backward travel of the wedge blocks 17, thereby immediately releasing the frictional contact and overcoming any tendency to bind, so 45 that the wear of the parts is reduced to a minimum and their easy successful operation facilitated.

While the use of acute-angled wedges is 50 of great advantage and the separating effect is increased in proportion to the force of impact, limitations have heretofore existed by reason of the fact that quick separation has been prevented due to the binding action of such acute wedges. This disadvantage is 55 completely overcome in my present construction.

The operation of the apparatus will be 60 readily understood from the foregoing description. In buffing, the friction blocks 19 move to a sufficient extent into the casing 5 giving the necessary limited spring compression before the friction elements operate, and in pulling the springs are partly 65 compressed by the strap 3 operating through blocks 9 and 7. Upon release of pressure

from either direction, the resiliency of the springs will replace the parts in their normal or relative positions.

Having described my invention, what I claim is:

1. In a friction draft gear, the combination with the casing, of friction blocks, a buffing block, a wedge block engaging the casing, a buffing block engaging the draw bar, and differential angle wedge blocks interposed between the friction blocks and the buffing block, substantially as set forth. 70

2. In a friction draft gear, the combination with the casing, of friction blocks, a buffing block, a wedge block engaging the friction blocks, and differential angle wedge blocks interposed between the buffing block and wedge block and friction blocks, substantially as set forth. 75

3. In a friction draft gear, the combination with the casing and the relatively movable draw bar; of friction blocks engaging the casing having inner inclined faces, a buffing block engaging the draw bar having outer inclined faces of different angle from the angle of the faces of the friction blocks, and wedge blocks interposed between the friction blocks and the buffing block having differential angles corresponding to and engaging said faces of the friction blocks and 95 buffing block respectively, substantially as set forth. 85

4. In a friction draft gear, the combination with the casing, of friction blocks, a buffing block, and interposed wedge blocks 100 having outer faces engaging the inner faces of the friction blocks and inner faces of steeper inclination engaging the outer faces of the buffing block, substantially as set forth. 105

5. In a friction draft gear, the combination with the casing, of friction blocks, a buffing block, and interposed wedge blocks having outer faces engaging the inner faces of the friction blocks and inner faces disposed at a more obtuse angle to the longitudinal center of the buffing block and engaging corresponding faces thereof, substantially as set forth. 110

6. In a friction draft gear, the combination with the casing, of friction blocks, a buffing block, differential angle wedge blocks interposed between the friction blocks and buffing block, and a wedge block engaging the friction blocks and said differential 115 angle wedge blocks, substantially as set forth. 120

7. In a friction draft gear, the combination with the casing and the relatively movable draw bar; of friction blocks engaging the casing and provided with terminal flanges, a buffing block engaging the draw bar, a wedge block engaging the flanges of the friction blocks, and differential angle wedge blocks interposed between the friction 125 130

blocks and buffing block and engaging the wedge block, substantially as set forth.

8. In a friction draft gear, the combination with the casing, its terminal bearing block, the relatively movable draw bar, and the yoke secured to the draw bar and embracing the terminal bearing block; of friction blocks engaging the casing, a buffing block engaging the draw bar, differential angle wedge blocks interposed between the friction blocks and buffing block, and spring mechanism interposed between the terminal bearing block and the friction blocks, substantially as set forth.
15. 9. In a friction draft gear, the combination with the casing, its terminal bearing block, the relatively movable draw bar, and the yoke secured to the draw bar and embracing the terminal bearing block; of friction blocks engaging the casing and provided with terminal flanges, a buffing block engaging the draw bar, a wedge block engaging the flanges of the friction blocks, differential angle wedge blocks interposed between the friction blocks and buffing block and engaging the wedge block, and spring mechanism interposed between the terminal bearing block and the flanges of the friction blocks, substantially as set forth.
25. 10. In a friction draft gear, the combination with the casing, yoke and draw bar; of

friction blocks, a buffing block, differential angle wedge blocks, a co-acting wedge block engaging the friction blocks, spring mechanism, and draw bar and yoke mechanism arranged to transmit movement to said parts, substantially as set forth.

35. 11. In a friction draft gear, the combination with the casing, yoke and draw bar; of friction blocks, a buffing block, differential angle wedge blocks, a co-acting wedge block engaging the friction blocks, spring mechanism, a draw bar engaging the buffing block, a bearing block engaging the spring mechanism, and a yoke connecting the bearing block with the draw bar, substantially as set forth.

40. 12. The combination with the central wedge-faced buffing block, the friction shoes and casing, and the differential angle wedge blocks; of a supplemental wedge block providing a telescoping longitudinal bearing for the end of the buffing block and engaging the differential angle wedge blocks, substantially as set forth.

45. 55. In testimony whereof I affix my signature in presence of two witnesses.

JOHN F. COURSON.
